UNITED STATES PATENT OFFICE

116,821

DESIGN FOR A CURTAIN OR SIMILAR ARTICLE

Abraham Holtz, Clarks Summit, Pa.

Application July 8, 1939, Serial No. 85,913

Term of patent 3½ years

To all whom it may concern:

Be it known that I, Abraham Holtz, a citizen of the United States of America, residing in Clarks Summit, in the county of Lackawanna and State of Pennsylvania, have invented a new, original, and ornamental Design for a Curtain or Similar Article, of which the following is a specification, reference being had to the accompanying drawing, constituting a part thereof.

The figure is a plan view of a curtain showing my new design.

I claim:

The ornamental design for a curtain or similar article, as shown.

ABRAHAM HOLTZ.
